UNITED STATES PATENT OFFICE.

BERT R. BENJAMIN, OF OAK PARK, ILLINOIS, ASSIGNOR TO INTERNATIONAL HARVESTER COMPANY OF NEW JERSEY, A CORPORATION OF NEW JERSEY.

HEAD-HOLDER FOR GRAIN-BINDERS.

1,226,629.

Specification of Letters Patent.

Patented May 22, 1917.

Application filed April 11, 1914. Serial No. 831,104.

To all whom it may concern:

Be it known that I, BERT R. BENJAMIN, a citizen of the United States, residing at Oak Park, in the county of Cook and State 5 of Illinois, have invented certain new and useful Improvements in Head-Holders for Grain-Binders, of which the following is a full, clear, and exact specification.

My invention relates to head holders for 10 grain binders.

In my prior Patent No. 1,029,741, patented June 18, 1912, I have described and claimed a two-part jointed head holder for binders adapted to rotate with the knotter 15 shaft of the binder and normally lie in engagement with the binder deck in such a manner as to prevent the heads of long grain from dropping down and hanging over the binder deck to too great a degree.

20 My present invention has for its object to improve the construction of such or other head holders of the rotatable type by providing improved means for attaching a part thereof to the knotter shaft whereby the 25 head holder is secured to the knotter shaft and made adjustable with respect thereto in such an improved manner that it may be readily adapted to different grain conditions. I attain these objects by means of 30 improved attaching and adjusting means for the head holder hereinafter more fully described.

In order that my invention may be clearly and fully understood, I have illustrated 35 three embodiments of it in the accompanying drawings.

In these drawings:

Figure 1 is a perspective view of a binder equipped with an improved form of my invention;

Fig. 2 is a similar view looking in the opposite direction;

Fig. 3 is a detail view of this form of attaching means;

Fig. 4 is a sectional view, taken along line 4—4 of Fig. 3, looking in the direction of the arrow;

Fig. 5 is a detail view of a modified form of my improved construction; and

Fig. 6 is a detail view of a further modified form of the same.

In the construction shown in Figs. 1 to 4 the bracket member 1 is carried upon the discharge arm 2, which, in turn, is carried 55 on the knotter shaft 3 of the binder 4, and

is rotatable with that shaft in a well-known manner. This bracket 1 is preferably in the form of a casting and is provided with an upper lip, ledge or hook 5 adapted to fit over one of the lateral flanges on the top 60 of the discharge arm, and is also provided with a downwardly extending body portion 6 adapted to lie alongside the web of the discharge arm, which body portion has a lower laterally protruding lug or ledge 7 65 thereon adapted to underlie the lip 5 and form therewith a channel in which the arm 2 is received. In this lower ledge or lug 7 an upwardly and angularly disposed opening or slot 8 is formed which is adapted to 70 receive and hold at an angle to the discharge arm the upper end of the upper section 9 of the head holder, which is also preferably cut off angularly so that it may underlie the flange on the opposite side of the arm 2 75 from the casting 1. In order to clamp the parts securely together a nut and bolt connection 10 is provided which extends through the bracket 1 at a point beneath the discharge arm and serves to clamp the member 9 of the head holder to the bracket 1 in the relation shown in Fig. 3. Obviously, when desired, the bracket 1 and the head holder may be adjusted longitudinally of 80 the discharge arm 2 by simply loosening the nut on the bolt 10 and shifting the casting and head holder to the desired position.

In Fig. 5 I have illustrated a modified form of this construction, wherein a member 11, corresponding somewhat to the 90 bracket 1, is fixed to the web of the discharge arm by a bolt 12 extending transversely through the web and the casting. This member 11 is provided with a laterally extending lower flange or lip projecting laterally underneath and beyond the lower edge of the web on the discharge arm, and is also provided with a slot or opening therein disposed at an angle to the discharge arm and in substantially the same manner 95 as the opening 8 previously referred to. Through this opening the upper member 9 of the head holder extends into substantially the same position occupied by it in the construction heretofore described; but in this 100 instance the bolt 12, passing through the web of the discharge arm, serves to directly clamp together the head holder 9, the bracket 11 and the web of the discharge arm. Obviously, in this construction the bracket 105 110

11 and the head holding member 9 are both secured to the discharge arm 2 by the bolt 12, and by providing a longitudinally disposed series of holes 13 the parts may be adjusted longitudinally to vary the position of the head holder as in the construction heretofore described.

In Fig. 6 I have shown a further modified form of my construction, wherein, instead of being attached to the discharge arm, the adjustable head holder connection is made to a supplemental arm 14 attached to the knotter shaft 3 by the set screw 15 or any suitable means and protruding radially from that shaft. This member 14 is provided with a longitudinally extending slot or channel 16 adapted to receive the upper end of a curved upper head holding member 17 of substantially the shape of a right angle, a slot and bolt connection 18 being provided between the member 14 and this member 17 so that the latter can be adjusted longitudinally with respect to the former, the member 17 in this instance being provided with the slot, while the bolt is carried by the member 14.

It will, of course, be understood that the form of my invention shown in Figs. 1, 4 and 5 may obviously be adapted to use in connection with a supplemental arm projecting radially from the knotter shaft in the same manner as the arm 14 described in connection with the section shown in Fig. 6; or even, in fact, to any member rotatable with that shaft. It is further to be understood that in all of these constructions a lower swinging head holder member 19 is preferably pivotally attached to the lower end of the head holding member 9, so that, when the shaft 3 is rotated, the two head holding members will move therewith; as, for instance, illustrated in dotted lines in Fig. 6, the lower or swinging head holding member 19 normally engaging with the deck of the binder when the knotter shaft is at rest, and swinging around again into engagement with the deck when the knotter shaft is actuated.

Obviously, in all of these instances, when, upon variation in the grain conditions, the operator desires to vary the position of the heads upon the binder deck, he may readily do so by simply loosening the connection of the upper head holder to the part rotating with the knotter shaft, and then sliding the bracket and head holder longitudinally of that part to the desired position, whereupon, by tightening this connection, the parts are locked against accidental longitudinal movement and relative angular displacement.

While I have in this application specifically described three forms which my invention may assume in practice, it is, of course, to be understood that the forms

thereof may be varied without departing from the spirit of my invention, and that I do not intend to limit myself to the details of construction illustrated.

What I claim as my invention, and desire to secure by Letters Patent, is:

1. In combination, a shaft, a rotatable member thereon, a head holder member, means for clamping said members together, and means on said clamping means coöperating with the side edges of said holder member for holding the same against angular movement with respect to said first mentioned member.

2. In combination, a shaft, a rotatable member thereon, a head holder member, means for clamping said members together, and means engageable by said holder member and disposed at one side of said clamping means for holding said holder member against any angular movement with respect to said first mentioned member.

3. In combination, a shaft, a rotatable member thereon, a head holder member, and operative connections between said holder member and said first mentioned member whereby said holder member may be adjusted longitudinally of said first mentioned member and locked against angular movement with respect thereto in each position of adjustment.

4. In combination, a shaft, a rotatable member thereon, a head holder member, a bracket on said first mentioned member having means holding said holder member against angular movement with respect thereto, and means for clamping said bracket and said holder member to said first mentioned member.

5. In combination, a knotter shaft, a head holder member, a bracket adjustable longitudinally of said first mentioned member, means for clamping said bracket and holder member to said first mentioned member, and means on said bracket coöperating with said clamping means preventing angular displacement of said holder member with respect to said first mentioned member.

6. In combination, a discharge arm having a substantially vertically disposed web, a bracket member having a laterally extending lip protruding beneath and beyond the lower edge of said web, said lip having a slot therein, a head holder extending through said slot, and a bolt clamping said bracket and head holder to said discharge arm.

7. In combination, a knotter shaft, a member rotatable therewith having a lateral extension thereon, a depending head holder member having a portion thereof underlying said extension, and means for clamping said head holder to said member disposed beneath said extension and coöperating therewith in holding said head holder member against angular movement.

8. In combination, a shaft, a rotatable member thereon having a lateral extension, a slotted bracket carried on said member, a depending head holder member having a portion thereof extending through said slotted bracket and underlying said extension, and means for clamping said bracket and holder member to said first mentioned member disposed beneath said extension and 10 coöperating therewith in maintaining said head holder member against angular movement.

9. In combination, a discharge arm having a substantially vertically disposed web, 15 a bracket member having a laterally extending lip protruding beneath and beyond the lower edge of said web, said lip having a slot therein, a head holder extending through said slot, and means for clamping said bracket and head holder to said discharge arm whereby said bracket and head holder may be adjusted longitudinally of said discharge arm.

10. In combination, a shaft, a radially extending rotatable member thereon, a head holder member, a bracket on said radially extending member having means for holding said holder member against angular movement with respect thereto, supplemental 30 means engageable by said holder member and carried on said radially extending member coöperating with said holding means, and

means for clamping said holder member and bracket to said radially extending member.

11. In combination, a knotter shaft, an arm extending radially therefrom, a bracket having a lip thereon extending over one edge of said arm and a coöperating lip extending under another edge thereof, said coöperating lip having an angularly disposed opening 40 therein, a head holder extending through said opening and engaging the side of said arm, and a bolt for clamping said bracket and head holder to said arm.

12. In combination, a discharge arm of substantially T-shaped cross section, a bracket having a lip extending over one of the flanges of said arm and a lug extending under the web thereof, said lug having an angularly disposed opening therein, a head 50 holder extending through said opening and into proximity to the flange on said arm on the opposite side from that engaged by said lip, and a bolt extending through said bracket and head holder at a point beneath 55 the web of said discharge arm clamping the two parts together.

In testimony whereof I affix my signature, in the presence of two witnesses.

BERT R. BENJAMIN.
